UNITED STATES PATENT OFFICE.

WILLIAM W. OWEN, OF ELGIN, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

1,359,913.

Specification of Letters Patent.

Patented Nov. 23, 1920.

Application filed May 11, 1917. Serial No. 167,862.

To all whom it may concern:

Be it known that I, WILLIAM WALTER OWEN, a citizen of the United States of America, and a resident of Elgin, county of Kane and State of Illinois, have invented certain new and useful Improvements in Measured - Service Telephone Systems, of which the following is a specification.

My invention relates in general to measured service telephone systems and has particular reference to measured service equipment for use in operating a subscriber's meter.

More specifically my invention relates to automatic means for accurately registering long distance connections on a subscriber's meter when connection is established between subscribers in exchanges which lie some distance apart and which connection must be extended through a number of intervening exchanges, whereby the subscriber may be charged according to the distance over which he extends the call, and the use of a supervising operator may be dispensed with.

These and other objects of my invention will be more readily understood by reference to the accompanying drawings, in which I have illustrated one embodiment of my invention in connection with automatic switches of well known type and construction. But I wish it to be understood that my invention may be used in connection with any well known type of switches.

In Figures 1, 2, 3 and 4 I have shown a pair of subscribers A and A' connected for conversation through a line switch C, selector E, and selector-repeater F of a first exchange (Figs. 1 and 2) through an incoming selector E' and a selector repeater F' of a second or intervening exchange (Fig. 3) and through incoming selector E² and a connector switch H of a third exchange (Fig. 4).

Fig. 5, shows another arrangement which may be used to control the register controlling device and will be explained later. Although the elimination of the operator in establishing local calls in one exchange and charging therefor has been made possible by the use of automatic switches and equipment it has become very necessary to provide some means whereby a subscriber may call either another subscriber in his own exchange or city or a subscriber in another

town or city without having to first call an operator. Some means must therefore be provided for automatically registering upon the calling subscriber's meter the proper charge which is to be made for calls over various length of trunk lines.

My invention is particularly adapted for use in a community where a number of towns or cities are closely associated and where the subscribers desire to call between cities quite frequently.

In order to accomplish this result I have provided a register controlling mechanism for each outgoing switch in an exchange, and which is operated in a step by step manner during the progress of the call through exchanges, and then released by the response of the called subscriber to send back a number of impulses to the calling subscriber's long distance meter J'. Each incoming trunk line coming into an exchange is provided with a device, which, when the trunk line is seized, sends a number of impulses back to operate the register controlling mechanism of the outgoing switch of the exchange in which the call originated according to the length of this trunk line. It will be seen therefore that a call may progress through any number of intervening exchanges, the trunk lines between which may be of various lengths and each of which may require a number of digits, and that each time the call extends to another exchange a number of impulses, according to the length of the trunk line to this exchange will be transmitted to the register controller, which will store up these impulses and return them to the subscriber's meter when the called for subscriber answers. Although I have shown two meters in this case, one for local calls and another for long distance calls it may be readily seen that one meter only could be used, namely meter J', and a connector of well known type, such as is shown in U. S. Patent No. 1,278,282, granted September 10, 1918, to Yanochowski & Hershey, used to send back an impulse over a simplex circuit when the called subscriber answers so that the meter would be operated once for local calls and a number of times for long distance calls.

Referring now to Fig. 1, the substation A may be of any well known common battery type and comprises the transmitter 2,

105

110

receiver 3, calling device 4, controlling the impulse springs 5 and 6, switch hook 7 for controlling the usual switch hook springs to disconnect the ringer 8 and condenser 9 and to connect the transmitter and receiver, in series with the impulse springs, across the line conductors 10 and 11 leading to the central office. In addition to this customary equipment, I have also provided a meter 10 J' which is connected to the mid point of a bridge which is normally connected across the line conductors 10 and 11 through the springs 12 and 13 and 14 and 15, and which are opened to disconnect said bridge while the calling device is being operated.

The line switch C in which the line conductors 10 and 11 terminate is similar in all respects to that shown in British Patent #1298 of 1910 and comprises among other details a plunger (not shown) attached to the end of a so called plunger arm 16, which is controlled by a magnet 17, to force into contact, in pairs, a bank of contact springs 18 to 25 inclusive, to thereby extend the line conductors 10 and 11 to a trunk line leading to a selector switch E.

The master switch D, for controlling the group of line switches similar to line switch C, is also similar to the master switch 30 shown in the above mentioned patent and need not be further described.

The selector switch E (Fig. 1) is similar in construction to that shown in United States Letters Patent #815,321, granted 35 March 13, 1906, to Keith, Erickson and Erickson, except that the side switch has been omitted and the circuits somewhat modified to adapt it to the modern two-wire system of operation. It comprises among 40 other details, a line relay 27, release relay 28, bridge cut-off relay 29, series relay 30, rotary interrupter relay 31, vertical and rotary magnets 33 and 32, and release magnet 34. The relays 28 and 30 are slow acting, that is slow to deenergize when their energizing circuits are broken, and control the switching over from the vertical to the rotary magnet. The line relay 27 controls the vertical and rotary magnets 33 and 32 to 45 raise the shaft wipers 35, 36 and 37 to some level of the banks and to rotate them into engagement with a pair of contacts in said level which lead to an idle selector repeater F (Fig. 2).

The selector repeater F is similar in construction to that shown in application Serial #655,985 of Talbot G. Martin filed October 21st, 1911, now Patent No. 1,312,558, Aug. 12, 1919, with the addition of a register controlling mechanism R adapted to control the subscriber's long distance meter J' in accordance with my invention, and certain relays and circuit arrangements for controlling said mechanism. It comprises 50 among other details a line relay 41, release

relay 42, back bridge relay 43, busy relay 45, series relay 44, private control relay 46, rotary interrupter relay 47, private magnet 48, and a pair of slow acting auxiliary relays 50 and 51. The line relay 41 operates 70 in response to impulses to first control the vertical and rotary magnets 52 and 53 to raise the wipers 64 to 67 inclusive, to some level of the banks and to then rotate them into connection with a set of contacts similar to 68 to 71 inclusive, the contacts 68 and 69 of which are connected to a trunk line leading to an incoming selector of another exchange. The release magnet 54 is also provided for restoring the switch to normal 75 after it has been operated. It will be noticed that this repeater F has four wipers 64 to 67 inclusive. The line wipers 64 and 65 are the only ones however which have connection leading beyond the switch, the 80 wipers 66 and 67 being used for selecting idle trunks in a sub-group, the trunk lines of each group or level, being divided into such sub-groups and the contacts 73 and 74 which are assumed to be the last of a sub-group being connected together, so that, as explained in the application above referred to, the wipers will rotate automatically over busy trunks of a sub-group until the last one is reached, when they will stop 85 whether this trunk is idle or busy, and if busy, return a busy signal to the calling subscriber.

Each selector repeater is also provided with a register controlling mechanism R, 100 comprising a ratchet wheel 61 rigid on a shaft, which is adapted to be rotated in a counter clockwise direction by means of a stepping magnet 60. A cam wheel 62 is loosely mounted on the shaft so that when 105 the ratchet is first operated the cam wheel remains stationary, but when the ratchet is released from its advanced position by the energization of release magnet 59, it is then rotated in a clockwise direction with the 110 ratchet wheel by means of the dog 63, and the clock spring not shown. The stepping magnet 60 is operated by impulses from special relays in another exchange over a simplex circuit, including the two trunk conductors leading to the other exchange in parallel and through the windings of the polarized back bridge relay 43, while the release magnet 59 is controlled over a local circuit by the back bridge relay when current over the two sides of the trunk in series is reversed by the response of the called subscriber. A relay 72 is provided which is substituted for the stepping magnet 60 in the simplex circuit when the selector repeater is seized by an incoming selector and operates to repeat the impulses over the simplex circuit to the preceding exchange.

Associated with the trunk line 86 and 87 which leads to an incoming selector is an 110

other exchange are a pair of relays 84 and 85, the function of which is to transmit back to the register controlling mechanism R, one or more impulses of current over a simplex 5 circuit. These relays are arranged to send one impulse in this case. The relay 84 energizes as soon as the release relay of the selector energizes and closes a bridge, the middle point of which is connected to battery, across the trunk conductors 86 and 87, a circuit is also closed by the relay 84 for the relay 85 which disconnects the relay 84 and locks itself up through a contact of the bridge cut-off relay 77, when the bridge 10 cut-off relay energizes these two relays are disconnected from their controlling relays.

The selector switch E' (Fig. 3) is similar to the selector E (Fig. 1) with the exception of the magnet 75, which is legged off from 15 the release trunk to increase the current flowing thereover to the next switch for purposes which will be explained. The selector repeater F' (Fig. 3) is exactly similar to the selector repeater F (Fig. 2). The selector E' (Fig. 4) is exactly similar to the selector E' (Fig. 2). It will be noticed that another set of relays similar to the relays 84 and 85 (Fig. 3) are associated with the trunk leading to selector E' except that in 20 this case the trunk line is assumed to be double the length of trunk line 86 and 87 and therefore another relay is added so that two impulses of current are returned to the mechanism R as soon as this trunk is seized. The connector switch H (Fig. 4) is similar 25 in construction to that shown in U. S. Letters Patent #815,176 granted March 13, 1906 to Keith, Erickson and Erickson, except that the circuits have been somewhat modified to adapt it to the modern two-wire system of operation.

The called substation A' and its associated line switch C' are similar in all respects to the calling station A and line switch C (Fig. 1).

Having given a general description of the apparatus involved I will now explain in detail how a subscriber at substation A may obtain connection with a subscriber at substation A', and how the proper charge for such call may be automatically charged on the calling subscriber's meter.

Upon the removal of the receiver at the substation A a circuit is closed by the hook 55 switch springs for the line winding 25 of line switch C from ground G' through springs 20 and 21, conductor 11, substation A, conductor 10, springs 23 and 22, and winding 25 to battery B. The winding 25, upon energizing, closes a circuit from ground G' through springs 20 and 20', pulling winding 26 and auxiliary winding 26 to battery B. The winding 19 upon energizing, attracts the plunger arm 16 and forces 60 the plunger (not shown) into the bank of

terminals before which it is held by the master switch D, thereby pressing the springs 18 to 21 inclusive, into contact with the springs 22 to 25 inclusive to extend the line conductors 10 and 11 to the selector 70 switch E. A circuit is thereby closed for the line relay 27 extending from ground G' through the lower winding of relay 27, springs 98 and 97, springs 23 and 19, conductor 11, substation A, conductor 10, right 75 hand winding of meter J, springs 18 and 22, springs 89 and 88, and upper winding of relay 27 to battery R'. The meter J does not operate at this time as current flows in opposite directions in the two windings. The 80 line relay 27 upon energizing, closes a circuit from ground G' through springs 99 and 100 and relay 28 to battery B'. Relay 28 is a slow acting relay and maintains a holding ground on the release trunk to hold the line 85 switch C in operated position. This circuit extends from ground G' through springs 102 and 103, springs 24 and 20 and winding 18 to battery B.

When the calling device of the substation 90 A is operated for the first digit of the called number, the line relay 27 of the selector E energizes and deenergizes in response to the opening and closing of the line circuit by the springs 5 and 6. In response to this operation of the line relay the vertical magnet 33 is first operated to step the wipers 35, 36 and 37 to some level of the banks and the rotary magnet 32 is then brought into operation to automatically rotate said wipers into 95 engagement with an idle set of contacts in this level, in this case 38, 39 and 40, which lead to a selector repeater F which is used in outgoing calls and has access to outgoing 100 trunk lines. As soon as the wipers come to rest on an idle trunk, the relay 29, which is short circuited during the rotation over busy trunks by a ground potential on the private contacts, energizes to disconnect the operating magnets of the selector from the trunk 105 conductors and to extend the connection to the conductors leading to said selector repeater. The circuit for the cut-off relay 29 extends from ground G' through springs 102 and 103, relay 29, interrupter springs 110 115 104 of the rotary magnet, off-normal springs 105, and relay 31 to battery B'. The relay 29 is of sufficiently high resistance to prevent enough current flowing over this circuit to operate the relay 31.

As soon as the relay 29 energizes a circuit is closed for the line relay 41 of the selector repeater F (Fig. 2) which extends from ground G' through the lower winding of relay 41, springs 106 and 107, contact 40, 120 wiper 37, springs 96 and 97 and over the previously traced circuit to and through the substation A and back over the other side of the line through springs 89 and 90, wiper 85, contact 38, springs 110 and 109, and 125 130

through the upper winding of relay 41 to battery B³. Relay 41, upon energizing, closes a circuit from ground G⁶ through springs 112 and 113, and through relay 42 to battery B⁴. Relay 42 energizes over the above circuit and prepares a circuit for the vertical magnet and also supplies a holding ground to the magnet 29 and winding 18 of the switches E and C. This holding circuit extends from ground G⁷ through springs 115, relay 51, contact 39, wiper 36, springs 92 and 93, relay 29, and through the relay 31 to battery B². A branch of this circuit extends through springs 24 and 20 and holding winding 18 to battery B. The relay 51 of selector repeater F is a marginal relay and does not energize over this circuit.

Upon the calling device at the substation A being operated for the next digit, the line relay 41 of the selector repeater F operates in response thereto to control the circuit of the vertical magnet 52, to step the wipers 64, 65, 66 and 67 to some level of the banks in which a certain group of contacts lead to incoming selectors of another exchange. The circuit of the vertical magnet extends from ground G⁶ through springs 112 and 114, springs 116 and 117, relay 44, vertical magnet 52, and side switch wiper 58 to battery B⁵. Relay 44 energizes and remains energized during the operation of the relay 41 and closes a circuit for the private magnet 48 from ground G⁸ through springs 119 and 120 and private magnet 48 to battery B⁶. When the relay 44 deenergizes after this series of impulses cease the circuit of the private magnet is opened and said magnet deenergizes to allow the side switch to pass from first to second position. The battery B⁵ is thereupon switched from the vertical to the rotary magnet so that when the calling device is operated for the next digit the rotary magnet is operated by the line relay 41 and operates to rotate the wipers 64, 65, 66 and 67 into connection with the first set of contacts of the desired subgroup of trunks leading to the desired exchange and to then automatically return to said wipers into connection with an idle set of contacts in said sub group. As soon as the impulses for this third digit cease, the slow relay 44, which was also energized in series with the rotary magnet, deenergizes and allows the private magnet to de-energize and trip the side switch to third position. The side switch wiper 56 upon passing to third position extends a guarding potential via the private wiper to the multiples of the private contacts in the banks of all switches which have access to this trunk. The side switch wiper 57 on passing to third position closes a bridge across the trunk conductors 86 and 87 which includes the windings of the polarized back bridge relay 43, thereby providing an energizing

circuit for the line relay 76 of the selector E' (Fig. 3) which extends from ground G⁹ through the lower winding of relay 76, springs 122 and 123, trunk conductor 87, contact 69, wiper 65, side switch wiper 57, back bridge relay 43, springs 166 of line relay 41, wiper 64, contact 68, trunk conductor 86, springs 124 and 125, and upper winding of relay 76 to battery B⁷. The current in this circuit is not in the proper direction to energize the polarized back bridge relay 43.

It is not thought necessary to further explain the operation of the selector repeater F as its operation is fully explained in said application #655,985.

Upon the line relay 76 energizing a circuit is closed from ground G¹⁰ through springs 126 and 127 and relay 78 to battery B⁷. Relay 78, upon energizing, prepares the circuit for the vertical magnet as usual and also closes a circuit from ground G¹¹ through springs 128 and 129, springs 130 and 131, springs 132 and 133 and relay 84 to battery B⁸. Relay 84 upon energizing, operates to deliver an impulse of current over a simplex circuit to the stepping magnet 60 of the register controlling mechanism. This simplex circuit extends from battery B²⁰, through the windings 142 and 143 in parallel, trunk conductors 86 and 87 in parallel and windings of back bridge relay 43 in parallel, resistance 144, springs 145, springs 146, and magnet 60 to ground G²¹. The relay 84 also closes a circuit from ground G¹⁴ through springs 138 and 139, relay 85, and springs 147 and 148 to battery B¹⁹. The relay 85 in turn energizes and opens the circuit of relay 84 and locks itself to ground G¹³ through springs 140 and 141. It will be seen therefore that only a momentary impulse is transmitted to the magnet 60 over the simplex circuit. The magnet 60 operates in response to this impulse to attract its armature and step the ratchet wheel 61 one step in a counter clock wise direction where it is held by the armature of release magnet 59 which normally rests in engagement with the teeth of said ratchet. The cam wheel 62 being loosely mounted upon the same shaft with the ratchet does not move at this time.

When the calling device is operated for the next digit of the called number, the line relay 41 is operated in the same manner as for the preceding digit, but in this case, the side switch being in third position, the impulses are repeated over the trunk line 86 and 87 by means of the springs 166 of said line relay. The springs 166 open and close the previously traced circuit of the relay 76 and also the slow acting relay 50 is energized to remove the impedance of the back bridge relay 43 from the impusing circuit. The line relay 76 is therefore operated to raise the wipers 149, 150 and 151 to some

level of the banks, whereupon the rotary magnet is automatically operated to rotate said wipers into connection with some trunk line leading to a selector repeater which has 6 access to outgoing trunks from this exchange in this case the selector repeater F'. The operation of the selector E' is like that explained in connection with selector E (Fig. 1). As soon as the wipers 149, 150 10 and 151 come to rest on the contacts 152, 153 and 154 the cut-off relay 77 is energized in the manner explained in connection with relay 29 of switch E and operates to disconnect the magnets from the trunk conductors and to extend the connection to the seized selector repeater. Relay 77 also opens the locking circuit for the relay 85 and also the initial energizing circuit for the relay 84 at the springs 147 and 148 and 130 and 131 15 so that said relays return to normal position. As soon as relay 77 energizes a circuit is closed for the line relay 155 of the selector repeater F' which extends from ground G¹⁵ through the lower winding of relay 155, springs 162 and 165, contact 153, wiper 150, springs 164 and 123, conductor 87, contact 69, wiper 65, side switch wiper 57, windings of relay 43, springs 166, wiper 64, contact 68, trunk conductor 86, springs 124 and 163, 20 wiper 149, contact 152, springs 158 and 160, and upper winding of relay 155 to battery B¹¹. The line relay 155, upon energizing, closes a circuit for the slow acting release relay 156 extending from ground G¹⁶ 25 through springs 168 and 167 and relay 156 to battery B¹². The relay 156 energizes over this circuit and operates to open the circuit for the release magnet and to prepare the circuit of the vertical magnet 170. A circuit is also closed by the relay 156 for supplying a holding ground to the cut-off relay 77 of the selector E' and which ground also makes the selector repeater busy to other 30 selectors. This circuit extends from ground G¹⁷ through springs 179 and 180, relay 178, contact 154, wiper 151, springs 181 and 182, and through relays 77 and 80 in parallel with the resistance 75 to battery. The comparatively low resistance of the magnet 75 35 allows sufficient current to flow over the above circuit to energize the relay 178 of the selector repeater F'. It may be here noted that all incoming selectors, that is switches which are accessible to other exchanges, are provided with a resistance similar to 75. The purpose of this resistance being to cut off the resistor controller of a selector repeater when it is used for a through call, as only the register control 40 mechanism of the outgoing switch in the originating exchange is used, so that no matter how many exchanges the call may pass through, only one controlling mechanism will be used. The relay 178 of the selector repeater, upon energizing over this circuit, 45

operates to disconnect the stepping magnet 176 and the release magnet 174 of the register controlling mechanism R' and to substitute the relay 176 in the simplex circuit in place of the stepping magnet for purposes which will be explained. 70

When the calling device is operated for the next digit of the called number, the circuit of the line relay 41 is again broken a number of times and, upon each deenergization, operates to separate the springs 166 and to thereby open the bridge across the trunk conductors 86 and 87, which operation results in the operation of the line relay 155 of the selector repeater F' (Fig. 3) in accordance with said digit to raise the wipers 183, 184, 185 and 186 to some level of the banks in a manner well known. The slow acting relay 173 of the selector repeater F' is connected in series with the vertical magnet and 85 remains energized during the entire operation of said magnet. In its operated position relay 173 closes a circuit for the private magnet 172 from ground G¹⁸ through springs 191 and 192 and private magnet 172 to battery B¹³. As soon as the impulses for the vertical magnet cease the relay 178 deenergizes and opens the circuit of the private magnet 172 whereby the side switch is tripped to second position. When the calling device is operated for the next digit the line relay 41 of selector repeater F is again operated to repeat a series of impulses to the line relay 155 of selector repeater F', which in this case (the side switch being in 90 second position) control the rotary magnet 171 to rotate the wipers 183, 184, 185 and 186 into connection with the first trunk line of a sub group which leads to the selector switches of a desired exchange, whereupon 95 the wipers are automatically rotated to an idle one of said trunk lines through the medium of relays 194 and 195. In case all the trunk lines of a desired group of trunks are busy the wipers will come to rest upon the 100 last trunk line thereof and the calling subscriber will be given a 'busy' signal through the medium of relay 193, which is controlled over the fourth wiper 186. As soon as the wipers come to rest on the contacts 187 and 115 188, the side switch is permitted to pass to third position. The side switch wiper 196 extends a guarding ground from ground G¹⁹ to the multiplied private contacts of the banks, and the wiper 197 upon passing to 120 third position closes a bridge across the trunk conductors 199 and 200 including the back bridge relay 157 and the line relay springs 198. This last operation provides an energizing circuit for the line relay 201 125 of the selector switch E² (Fig. 4) which extends from ground G²⁰ through the lower winding of relay 201, springs 207 and 208, trunk conductor 200, contact 188, wiper 184, side switch wiper 197, winding of the back 130

bridge relay 157, springs 198, wiper 183, contact 187, trunk conductor 199, springs 209 and 210, and upper winding of relay 201 to battery B^{14} . The current in this circuit is 5 not in the proper direction to energize the polarized back bridge relay 157 but the line relay 201 of the selector energizes and closes a circuit for relay 202 from ground G^{22} through springs 211 and 212 and through 10 said relay 202 to battery B^{14} .

As soon as the slow acting relay 202 energizes a starting circuit is closed for the special impulsing relays 213, 214 and 215 in the same way that the relays 84 and 85 15 associated with the trunk 86 and 87, were started. This circuit extends from ground G^{21} through springs 203 and 204, springs 205 and 206, springs 228, springs 216 and 217, and relay 215 to battery B^{15} . The relay 215 is energized over this circuit and 20 operates to connect a bridge consisting of resistances 218 and 219 which are connected together to battery B^{16} at the mid point, across the trunk conductors 199 and 200, 25 through the springs 220 and 221. The springs 222 also engage at this time and close a circuit from the ground G^{23} through springs 222, springs 223, and relay 214 to battery B^{16} . The relay 214 on energizing 30 opens the springs 217 and 216 first and then closes springs 224 and 225. The opening of the springs 217 deenergizes the relay 215 which opens the bridge across the conductors 199 and 200 and the closure of springs 224 35 and 225 again closes said bridge across said conductors. The springs 226, closed by the operation of relay 214, close the circuit of slow acting relay 213 from ground G^{24} through springs 226, relay 213, and springs 40 227 to battery B^{17} . The relay 213, upon energizing, locks itself to ground 25 through springs 229 and opens the circuits of relays 215 and 214 at springs 228 and 223, respectively. It will be seen therefore that during 45 the operation of these relays, two impulses of current have been transmitted back over a simplex circuit to the preceding exchange. In this case the trunk line 199 and 200 is assumed to be double the length of 50 the trunk line 86 and 87, therefore requiring double the rate of charge. The impulses above mentioned pass from battery B^{16} through the windings 218 and 219 in parallel, springs 220 and 221, or 224 and 55 225, trunk conductors 199 and 200 in parallel, and through the windings of the back bridge relay 157 in parallel through the resistance 230, springs 231, and relay 176 to ground G^{26} . It will be remembered that 60 when the relays 84 and 85 of the trunk 86 and 87 were energized the impulses were repeated back over the simplex circuit to the stepping magnet of the register controller. In this case, however, the relay 176 is energized twice by said impulses and in turn 65 operates to close a bridge across the trunk conductors leading back to the preceding exchange, whereby the impulses from battery B^{16} are repeated back to the stepping magnet 60 of the register controller R (Fig. 2). 70 The circuit over which these impulses are repeated extends from battery B^{20} through the windings 232 and 233 in parallel, springs 234 and 235 in parallel, springs 236 and 237 in parallel and back over the trunk conductors and the windings of relay 43 in parallel through the stepping magnet 60 to ground G^{27} . The magnet 60 energizes twice over this circuit and operates to step the ratchet wheel 61 two more steps. 75

When the calling device is operated for the next digit the impulses are repeated first by the line relay 41 of selector repeater F to the line relay 155 of selector repeater F' and then repeated to the line relay 201 of the selector E² (Fig. 4). The relay 201 operates in response to this series of impulses to first raise the wipers 238, 239 and 240 opposite some level of the banks, at which time said wipers are automatically rotated 80 into connection with the contacts 241, 242 and 243 which lead to an idle connector switch H. As soon as the wipers come to rest, the relay 244 is energized in the usual manner and operates to disconnect the operating magnets of the switch and the special relays 213, 214 and 215 and to extend the connection through to the connector switch H. Upon this extension of the connection a circuit is closed for the line relay 245 of the connector switch H which extends from ground G^{28} through the lower winding of said relay, springs 247 and 248, contact 242, wiper 239, springs 251 and 208, conductor 200, contact 188, wiper 184, side switch wiper 197, relay 157, springs 198, wiper 183, contact 187, conductor 199, springs 209 and 252, wiper 238, contact 241 and through springs 249 and 250 and upper winding of relay 245 to battery B^{21} . The current is still in the 90 wrong direction to operate relay 157, but relay 245 energizes over this circuit and closes a circuit for relay 246 from ground G^{29} through springs 252 and relay 246 to battery B^{21} . Relay 246 in turn energizes and 95 prepares the circuit of the vertical magnet 253 and supplies a holding ground for the relay 244 of selector E² from ground G^{26} through the springs 254.

Upon the calling device being operated 100 for the last two digits, the line relay 41 of selector repeater F operates in accordance therewith and repeats said impulses to the line relay 155 of selector repeater F', which in turn, by means of springs 198, repeats 105 said impulses to the line relay 245 of connector switch H (Fig. 4) over the previously traced circuit. The line relay 245 in response to the first of said digits operates to raise the wipers 255, 256 and 257 through 110

115

120

125

130

the medium of the vertical magnet 253 to some level of the banks and in response to the last digit to rotate the wipers by means of the rotary magnet 261 into connection 5 with the contacts 258, 259 and 260 which are connected to the desired line.

Assuming the called line to be idle, the side switch will immediately pass to third position upon the cessation of said impulses 10 and the called subscriber's bell will be operated by the current from the generator I, which is applied to the called line intermittently through the medium of the ringing relay 262 and interrupter 263. The side 15 switch wiper 264 upon reaching third position, closes a circuit for the holding or cut off winding 265 of the line switch C' which operates to disconnect said line switch from the called line. Ground is also supplied through 20 said side switch wiper to the relay 266 which connects the trunk connection through to the called subscriber's line.

The called subscriber upon removing his receiver in response to the signal, closes a 25 circuit for the back bridge relay 267 as follows: from ground G³¹ through the lower winding of relay 267, springs 268, springs 270, wiper 256, contact 259, substation A', springs 271 which were closed by the energization of the cut off winding 265, contact 30 258, wiper 255, springs 272, springs 273 and upper winding of relay 267 to battery B²². The back bridge relay 267, upon energizing over this circuit, operates to close the circuit 35 of the ring cut off relay 269 and to reverse the connections of the line relay 245 to the trunk conductors in a well known manner. The relay 269 energizes and opens the circuit of the ringing relay 262, and locks itself 40 to ground at the off normal springs.

This reversal of the connections of line relay 245 to the trunk conductors, reverses the flow of current in the previously traced circuit including said line relay 245 and the back bridge relay 157 of the selector repeater F'. The back bridge relay, which has up to this time remained in normal position, energizes in response to this reversal of current and operates to in turn reverse 45 the current in the trunk conductors back toward the calling man. Relay 157 also closes a circuit for the relay 174 at one point which has no effect at this time, due to the fact that relay 178 is energized and holds 50 said circuit open at another point. This second reversal of current in the trunk conductors 86 and 87 causes the back bridge relay 43 to energize in the same manner as relay 157, to in turn reverse the current back to the 55 calling line to operate the local call meter J, which is operated once only for each call, and also closes a circuit from ground G³² through springs 274, springs 275, and release magnet 59 of the register controller R to battery B²³. It will be remembered that re- 60

lay 51 of selector repeater F was not energized and therefore springs 275 will remain closed. The release magnet 59, upon energizing, withdraws its armature from the teeth of ratchet wheel 61 and allows said 70 ratchet to be returned to normal by the clock spring. This call having progressed through two exchanges, thereby using two long distance trunk lines, one of double the length required for a unit of charge, the ratchet wheel has therefore been operated 75 three times or three steps and upon returning to normal will carry the cam wheel 62 three steps in a clockwise direction, thereby forcing the springs 276 and 277 and 278 80 and 279 into contact three times momentarily. The result of this operation is to connect a bridge including the windings 280 and 281, which are connected to battery at the mid point, across the conductors leading 85 to the calling substation. The meter J' is thereby operated three steps by the impulses from battery B²⁴ through windings 280 and 281 in parallel, springs 279 and 278 and 277 and 276 in parallel, springs 282 and 283 in 90 parallel, and over the trunk and line conductors in parallel to the substation A, springs 12 and 13 and 14 and 15 in parallel, and windings 284 and 285 in parallel through the winding of meter J' to ground 95 G³³.

When conversation is finished the connection is released by the calling man in the usual manner. Let us assume that a call is set up and the called subscriber fails to 100 answer. In this case the register controller R will have been stepped around a number of steps. The relay 49 is provided, so that, when the release magnet 54 of the selector repeater is energized, a circuit will be closed 105 for the relay 49, which operates to close a circuit for the release magnet 59 of the mechanism R and to also open the simplex circuit which is controlled by said mechanism at the springs 282 and 283. It will therefore be seen that in an uncompleted, or unanswered call the mechanism R will be returned to normal without operating the subscriber's meter.

In case the called line is found to be busy 115 the usual busy signal is returned to the calling subscriber and the connection is released in the same manner as described above.

In Fig. 5 I have shown a modification of 120 one feature of my invention which comprises a rotary switch which may be used in place of the relays 84 and 85 or relays 213, 214 and 215, to repeat the impulses over the simplex circuit to the stepping magnet of the 125 register controller. This switch comprises a pair of wipers 286 and 287 whose function is to deliver impulses over a simplex circuit by opening and closing a bridge, comprising the windings 289 and 290 connected to bat- 130

terry B²⁵ at the mid point, across a trunk line. The third wiper 288 is provided for energizing the motor magnet 291 to rotate the three wipers in a step by step manner. The 5 springs 292 may be controlled by the release relay of a selector similar to relay 78 of selector E' (Fig. 3), and will operate to close an initial energizing circuit for the motor magnet 291, after which the wiper 288 will 10 maintain said circuit closed until the wipers have reached normal position. Any number of the contacts over which wipers 286 and 287 rotate may be connected together to give any number of impulses.

15 It will be seen therefore that I have provided a very efficient and flexible method of charging automatically for long distance calls, and that no matter how many exchanges a call may pass through, how large 20 said exchanges may be, or how long the trunk lines may be, the subscriber's meter will always be operated once for each unit 25 length of trunk line over which his call may have progressed. It will be understood that although I have shown the register controller 30 associated with a selector repeater of a certain type that it is equally as well adapted for use with simple repeaters, rotary connectors or any other switch which has access 35 to outgoing trunk lines. Also although I have shown a limited number of switches in each exchange it will be seen that each exchange may be of any size and a call may progress through any number of switches in 40 each exchange without affecting in any way the assessing of the proper toll. For convenience I have used two meters, one for local and one for long distance calls, however it is understood that one meter only may be 45 used and that this meter may be controlled in any well known manner.

Having fully described and illustrated my invention I will attempt to point out what I consider to be patentable in the appended 50 claims.

What I claim as my invention is:

1. In a telephone system, subscribers' lines, trunk lines of different character, means for extending a connection from a calling to a 55 called subscriber's line over said trunk lines, a meter for the calling line, a meter controlling device common to said lines, means associated with each trunk line for operating said device a predetermined number of times for each call to in turn operate said meter a 60 number of times to record charges varying in accordance with the trunk line used.

2. In a telephone system, subscribers' lines, trunk lines of different character, means for 65 extending a connection from a calling to a called subscriber's line over said trunk lines, a meter for the calling line, a meter controlling device, means associated with each trunk line for operating said device for recording charges varying in accordance with

the trunk line used when the device is released, and means for releasing said device.

3. In a telephone system, subscribers' lines, trunk lines of different character, means for extending a connection from a calling to a 70 called subscriber's line over said trunk lines, a meter for the calling line, a meter controlling device common to said lines, means individual to each trunk line for operating said device a predetermined number of times 75 for each call for recording charges on said meter varying in accordance with the trunk line used.

4. In a telephone system, subscribers' lines, trunk lines of different character, means for 80 extending a connection from a calling to a called subscriber's line over said trunk lines, a meter for the calling line, a meter controlling device, means associated with each trunk line for operating said device for recording charges varying in accordance with the 85 trunk line used when the device is released, and means for releasing said device controlled by the called subscriber.

5. In a telephone system, subscribers' lines, 90 trunk lines of different character, means for extending a connection from a calling to a called subscriber's line over said trunk lines, a meter for the calling line, a meter controlling device common to said subscribers' lines, 95 means associated with each trunk line for operating said device a predetermined number of times for each call for recording charges varying in accordance with the trunk line used.

6. In a telephone system, subscribers' lines, trunk lines of different character, means for extending a connection from a calling to a called subscriber's line over 100 said trunk lines, a meter for the calling line, a meter controlling device common to said lines, an impulse sender associated with each trunk line for operating said device a predetermined number of times for 105 each call for recording charges varying in accordance with the trunk line used.

7. In a telephone system, subscribers' lines, trunk lines of different character, means for extending a connection from a calling to a called subscriber's line over 110 said trunk lines, a meter for the calling line, a meter controlling device, means associated with each trunk line for operating said device over a circuit including the two sides 115 of said trunk lines in parallel for recording 120 charges varying in accordance with the trunk line used.

8. In a telephone system, subscribers' lines, trunk lines of different character, means for extending a connection from a calling to a called subscriber's line over 125 said trunk lines, a meter for the calling line, a meter controlling device, means associated with each trunk line for operating said device over a circuit including the two 130

- sides of said trunk lines in parallel, and means for releasing said device for rendering charges varying in accordance with the trunk line used.
5. 9. In a telephone system, subscribers' lines, trunk lines of different character, means for extending a connection from a calling to a called subscriber's line over said trunk lines, a meter for the calling line, a 10 meter controlling device common to said lines, means associated with each trunk line for operating said device a predetermined number of times for each call for recording charges varying in accordance with the 15 trunk line used upon the response of the called subscriber.
10. In a telephone system, a plurality of exchanges, a calling line in one exchange, a meter and a meter controller in said one 20 exchange, means for extending a call from said calling line through a plurality of said exchanges, means in each exchange for operating said device when the call is extended thereto, and means for releasing said device to in turn operate said meter.
11. In a telephone system, a plurality of exchanges, a calling line in one exchange, a meter and a meter controller in said one exchange, means for extending a call from 30 said calling line through a plurality of said exchanges, means in each exchange for operating said device in a particular manner when the call is extended thereto, and means for releasing said device to in turn operate 35 said meter.
12. In a telephone system, a plurality of exchanges, a calling line in one exchange, a meter and a meter controller in said one exchange, means for extending a call from 40 said calling line through a plurality of said exchanges, means in each exchange for operating said device when the call is extended thereto, and means controlled by the called subscriber for releasing said device 45 to in turn operate said meter.
13. In a telephone system, a calling and a called subscriber, a meter for the calling subscriber, an automatic switch accessible to said calling line for extending a call 50 therefrom, link circuits accessible to said switch, a step by step meter controller associated with said switch, means for connecting said calling line with said automatic switch, and for operating said switch to extend 55 a connection over a number of said link circuits to the called subscriber, means associated with each link circuit for automatically operating said controller a number of times when the connection is extended thereto and means controlled by the called subscriber for releasing said controller to thereby operate said meter in accordance with the length of the link circuits over which the connection extends.
- 60 14. In a telephone system, a calling and a called subscriber, a meter for the calling subscriber, an automatic switch accessible to said calling line for extending a call therefrom, link circuits accessible to said switch, a step by step meter controller associated with said switch, means for connecting said calling line with said automatic switch, and for operating said switch to extend a connection over a number of said link circuits to the called subscriber, means associated with each link circuit for automatically operating said controller a number of times when the connection is extended thereto and means controlled by the called subscriber for releasing said controller to thereby operate said meter in accordance with the length of the link circuits over which the connection extends.
- 65 15. In a telephone system, a calling line, a called line, means for connecting said lines by means of a series of trunk lines, a measured service device for the calling line, and means associated with each trunk line in the series for registering a charge upon said device for the use of such trunk line.
16. In a telephone system, a calling line, a called line, means for connecting said lines by means of a series of trunk lines, a measured service device for the calling line including a meter and a meter controller, and means associated with each trunk line in the series for registering a charge upon said device for the use of such trunk line.
17. In a telephone system, a calling line, a called line, means for connecting said lines by means of a series of trunk lines, a measured service device for the calling line including a meter and a meter controller, means associated with each trunk line for registering a charge upon said controller for the use of such trunk line, said meter in turn controlled by said controller to assess said charge thereon.
18. In a telephone system, a calling line, a called line, means for connecting said lines including a plurality of trunk lines, a measured service device for the calling line including a meter and a meter controller, means associated with each trunk line for registering a charge upon said controller for the use of such trunk line, said meter in turn controlled by said controller to assess said charge thereon when the called subscriber answers.
19. In a telephone system, a calling line, a called line, means for connecting said lines including a plurality of trunk lines, a measured service device for the calling line including a meter and a meter controller, means associated with each trunk line for registering a charge upon said controller for the use of such trunk line when connection is made therewith, said meter in turn con-

trolled by said controller to assess said charge thereon when the called subscriber answers.

20. In a telephone system, calling and called subscribers' lines, a register for each line, means for connecting any two of said lines over a plurality of trunk lines of different character, a register controller, means associated with each trunk line for variably adjusting said controller in accordance with the character of said trunk line, said register operated by said controller in accordance with the adjustment thereof to assess toll.

21. In a telephone system, calling and called subscribers' lines, a register for each line, means for connecting any two of said lines over a plurality of trunk lines of different character, a register controller, means associated with each trunk line for variably adjusting said controller in accordance with the character of said trunk line when connection is made therewith, said register operated by said controller in accordance with the adjustment thereof to assess toll.

22. In a telephone system, calling and called subscribers, a register for each line, means for connecting any two of said lines over a plurality of trunk lines of different character, a register controller, means associated with each trunk line for variably adjusting said controller in accordance with the character of said trunk line, said register operated by said controller in accordance with the adjustment thereof to assess toll when the called subscriber answers.

23. In a telephone system, calling and called subscribers, a register for each line, means for connecting any two of said lines over a plurality of trunk lines of different character, a register controller, means associated with each trunk line for variably adjusting said controller in accordance with the character of said trunk line when connection is made therewith, said register operated by said controller in accordance with the adjustment thereof to assess toll when the called subscriber answers.

24. In a telephone system, calling and called subscribers' lines, a meter for each line, trunk lines, means for extending a connection from a calling to a called line by means of said trunk lines, an impulse

sender for each trunk line, means for receiving and storing up a number of impulses from each impulse sender when the connection is extended to its associated trunk line, said means controlled from the called line to repeat said impulses to the meter of the calling subscriber to assess the proper toll.

25. In a telephone system, calling and called subscribers' lines, a meter for each line, trunk lines, means for extending a connection from a calling to a called line by means of said trunk lines, an impulse sender for each trunk line, means for receiving and storing up a number of impulses from each impulse sender when the connection is extended to its associated trunk line, said means controlled from the called line to repeat said impulses to the meter of the calling subscriber to assess the proper toll when the called subscriber answers.

26. In a telephone system, subscribers' lines, trunk lines of different character, means for extending connections from calling to called subscribers' lines over any of said trunk lines, a meter for the calling line, a meter controlling device common to said lines, means associated with each trunk line for operating the device a predetermined number of times, and means controlled by the response of the called subscriber for operating said device to in turn operate said meter in accordance with the predetermined number of times which the device was operated.

27. In a telephone system in which there are zones for calling arbitrarily established and a meter on each line adapted to be operated a variable number of times depending upon the number of zones through which a call has progressed when the called subscriber answers, means in each zone through which a call is successively extended for operating the meter one or a plurality of times in accordance with the charge for each zone the accumulated charge for all the zones through which the call progresses comprising the complete charge for the call.

Signed by me at Chicago, Cook county, State of Illinois, this 3rd day of May, 1917.

WILLIAM W. OWEN.
